TARGET BALLOON

Carl R. Weinert, West View, Pa., assignor to Federal Laboratories, Inc., Pittsburgh, Pa., a corporation of Delaware

Application April 7, 1947, Serial No. 739,984

3 Claims. (Cl. 102—37.1)

1

This invention relates to a target balloon adapted to be carried in folded condition by an airplane and to expand when dropped therefrom to present a target. A deficiency in target balloons known theretofore is that they occasionally fail to open so as to present a target. The present invention provides means for initially causing the ribs of the balloon to open, thereby positively initially opening the balloon so as to insure that it will present a target. In the preferred embodiment of the invention, a smoke grenade is associated with the balloon and the arrangement is such that after the balloon and the smoke grenade which is connected thereto have been dropped from the airplane, the balloon is caused by positive means to initially open and the grenade is actuated so as to emit smoke, thereby enabling one to locate the balloon more readily.

In the accompanying drawings which illustrate a preferred embodiment of the invention and certain modifications thereof,

Figure 1 is a vertical section through the folded balloon and smoke grenade, certain parts being shown in elevation;

Figure 2 is a vertical elevation of a sleeve which fits over the folded balloon and confines the lower ends of the ribs to prevent them from opening and to confine the safety lever of the smoke grenade to prevent it from operating;

Figure 3 is a horizontal section taken on the line III—III of Figure 1, illustrating the rib separator, the folded balloon being omitted;

Figure 4 is a horizontal section taken on the line IV—IV of Figure 1;

Figure 5 is a front elevation of the balloon and grenade after they have been dropped from the airplane and the balloon has opened and the grenade is in condition to emit smoke;

Figure 6 is a view, partly in side elevation and partly in vertical section of a modification in which the sleeve of Figure 1 is not used;

Figure 7 is a horizontal section taken on the line VII—VII of Figure 6;

Figure 8 is a view similar to Figure 6 but illustrating another modification in which an explosive charge is used in place of the shroud shown in Figure 6 for releasing a pin so as to allow the balloon to open and the smoke grenade to operate; and

Figure 9 is a side elevation of the lower portion of the arrangement shown in Figure 8, looking at a different side.

Referring more particularly to Figures 1 through 5, the balloon is shown in folded condition in Figure 1 and in open condition in

2

Figure 5. Referring to Figure 5, the balloon has a substantially closed top or crown 2, a vertical wall 3 and is open at the bottom. The crown has a reinforcing patch 4 and is provided with a small opening 5 which fits over the top 6 of a shaft 7 when the balloon is folded. Ribs 8 are pivoted at one end to a ring 9 secured to the shaft and at their other ends 10 are connected to the lower edge of the balloon at circumferentially spaced points. 5 Rib cables 11 are provided for limiting the opening movement of the ribs. These cables are connected at one end 12 to a ring 13 which is fixed to the shaft 7 and at their other ends 14 are pivotally connected to the ribs 8 intermediate the ends 10 of the ribs.

A rib spreader 15 is provided for opening the ribs initially so as to insure that the balloon will open when it is dropped from the airplane. The rib spreader is shown in detail in Figure 3. It 20 comprises a disc 16 and an integral sleeve portion 17. The rib spreader is secured to the shaft 7 by a bolt 18. The disc 16 is provided with notches 19 in its edge which receive the ribs 8.

A smoke grenade indicated generally by the 25 reference numeral 20 is secured to the lower end of the shaft 7 by a bolt 21. The smoke grenade is of conventional design and therefore need not be described in detail. It contains a charge of smoke emitting material and is provided with a firing mechanism for igniting the smoke charge, the firing mechanism being located in the head 22. A safety lever 23 having a handle 24 fits over the head 22 and prevents the firing mechanism from firing the smoke grenade when the 30 safety lever and handle are in the position shown in Figure 1. In addition the smoke grenade is provided with the usual safety pin 25 and ring 26 for withdrawing the pin.

A sleeve indicated generally by the reference 35 numeral 30 and shown in Figure 2 has an upper hood portion 31 which fits over the folded balloon as shown in Figure 1 and a lower sleeve portion 32 which is made of elastic material. The elastic band 32 acts as a confining means for confining the lower ends 33 of the ribs 8 and the lower edges 34 of the folded balloon in the position shown in Figure 1. The elastic band 32 also confines the handle 24 of the safety lever 23 so as to prevent the smoke grenade from operating when the parts 40 are in the position shown in Figure 1. A shroud or cord 35 has one end 36 connected to the upper end of the hood portion 31 of the sleeve 30. The other end of the shroud is connected to the airplane or is held by the person who is to drop the 45 balloon from the plane.

In dropping the balloon and causing it to open so as to present a target, the operation is as follows:

An end of the shroud 55 is connected to the airplane or is held in the hand of the one who is to drop the balloon. The safety pin 28 is then removed from the grenade. It will be understood that even though the safety pin has been removed, the grenade will not be fired because the handle 24 is retained in the position shown in Figure 1 by the elastic band 32 on the sleeve 30. The balloon is then dropped from the airplane. When the shroud has become extended to its full length it jerks the sleeve 30 and band 32 from the balloon. The rib spreader 15 then acts to initially open the ribs from their confined position shown in Figure 1. It will be understood that the rib spreader tends to cause the ribs to assume the chain line position 37 shown in Figure 1, that is, it tends to straighten out the ribs which previously have been confined by the elastic band 32 of the sleeve 30. The rib spreader accordingly acts as a positive means for initially opening or spreading the ribs 8. The balloon fills with air as it drops and the ribs are caused to open further. The opening movement of the ribs is limited by the rib cables 11 so that when fully opened the balloon has the shape shown in Figure 5.

When the sleeve 30 is jerked from the balloon it also releases the handle 24 of the grenade. This enables the handle to fly from the head 22 and allows the firing mechanism within the head to operate so as to cause smoke to be emitted from the grenade. The invention thus provides means for carrying a balloon in folded condition in an airplane, for causing positive initial spreading of the ribs and opening of the balloon when it is dropped and for causing the smoke grenade to operate so as to draw attention to the target balloon.

The device shown in Figures 6 and 7 is similar to that shown in Figures 1 through 5 except that no sleeve corresponding to the sleeve 30 is employed. The construction includes a balloon 40, shaft 41, ribs 42, rib spreader 43, rib cables 44, smoke grenade 45 and a safety lever 46 having a handle 47. The lower edges of the folded balloon, the lower ends of the ribs 42 and the handle 47 are confined by a resilient band 48 which may be a metal band which is held in closed position by a pin 49. The metal band 48 is formed in a manner similar to a hinge and has an upper eye portion 50 and a lower eye portion 51 spaced from the eye 50, both portions 50 and 51 being formed at one end 52 of the band. An eye 53 formed on the end 54 of the band fits into the space between the eyes 50 and 51 and the band is retained in closed position by the pin 49. A shroud 55 has its lower end 56 connected to the pin.

The device illustrated in Figures 6 and 7 operates in a manner similar to the device of Figures 1 through 5. The balloon is thrown from the airplane and the pin 49 is jerked from the band 48 thereby allowing the band to open. This allows the rib spreader 43 to initially spread the ribs 42 and the release of the handle 47 causes the grenade to be fired as previously described.

The device shown in Figures 8 and 9 includes a balloon 60, shaft 61, ribs 62, rib spreader 63, rib cables 64, grenade 65 safety lever 66 and safety lever handle 67. The band 68 for confining the handle 67 and lower ends of the ribs is a flexible metal band the same as in the device of Figures 6 and 7. The band 68 is retained in closed posi-

tion by a pin 69. The pin is caused to drop from the band by an arrangement including an explosive charge. As shown in Figure 8, a chamber 70 is secured to the band 68 and is arranged in alignment with the pin 69. The chamber contains an explosive charge 71, a delay train 72 of powder, a primer 73, a firing pin 74 and a spring 75. The firing pin is maintained in inoperative position by a cotter pin 76.

The operation of the device is as follows. The grenade safety pin 77 is removed and the cotter pin 76 is withdrawn and the folded balloon is dropped from the airplane. The removal of the cotter pin 76 causes the firing pin 74 to ignite the primer 73 and the delay train (time fuse) 72. After the balloon has dropped a predetermined distance, depending upon the delay train employed, the explosive charge 71 is ignited and causes the pin 69 to drop from the band 68. The band opens, releases the lower ends of the ribs 62 whereupon the rib spreader 63 becomes operative to initially open the balloon. The release of the handle 67 from the band 68 also causes the firing mechanism of the smoke grenade to operate.

In the preferred embodiment of the invention it comprises the combination of a target balloon and a smoke grenade. However certain features of the invention are of advantage whether or not the balloon is associated with a smoke grenade. Thus the smoke grenade could be eliminated and the various confining means described, such as the elastic band 32 of Figure 2, the resilient band 48 of Figure 6 or the resilient band 68 of Figure 8 would serve the purpose of confining the lower ends of the ribs in folded position and for confining the lower edges of the folded balloon. Upon release of the confining means, the rib spreader would operate to initially open the ribs in the manner which has been described even though no smoke grenade were associated with the balloon.

I have illustrated and described certain preferred embodiments of the invention. However, it is to be understood that the invention may be otherwise embodied or practiced within the scope of the following claims.

I claim:

1. A target balloon adapted to be carried in folded condition by an airplane and to expand when dropped therefrom to present a target, said balloon, when expanded, having a substantially closed top and an open bottom, said balloon comprising a shaft, a smoke grenade connected to the lower end of the shaft, said grenade having a firing mechanism and a safety lever for controlling the grenade firing mechanism, ribs pivoted at one end to the shaft and connected at their other ends to the lower edge of the balloon at circumferentially spaced points, means for limiting the opening movement of the ribs, a rib spreader connected to the shaft, means for confining the lower ends of the folded ribs and the lower edge of the folded balloon and said safety lever, said confining means opposing the tendency of the rib spreader to spread the ribs, and means for releasing said confining means after the balloon is dropped from the airplane, whereby the rib spreader acts to spread the ribs initially and the safety lever is released so as to cause the grenade to emit smoke.

2. A target balloon adapted to be carried in folded condition by an airplane and to expand when dropped therefrom to present a target, said balloon, when expanded, having a substantially closed top and an open bottom, said balloon com-

prising a shaft, ribs pivoted at one end to the shaft and connected at their other ends to the lower edge of the balloon at circumferentially spaced points, means for limiting the opening movement of the ribs, a rib spreader connected to the shaft, a fabric sleeve enclosing the folded balloon, a band of elastic material connected to the fabric sleeve for confining the lower ends of the folded ribs and the lower edge of the folded balloon, said band opposing the tendency of the rib spreader to spread the ribs, and a shroud connected at one end to said sleeve and at the other end to the airplane.

3. A target balloon adapted to be carried in folded condition by an airplane and to expand when dropped therefrom to present a target, said balloon, when expanded, having a substantially closed top and an open bottom, said balloon comprising a shaft, ribs pivoted at one end to the shaft and connected at their other ends to the lower edge of the balloon at circumferentially

spaced points, means for limiting the opening movement of the ribs, a rib spreader connected to the shaft, a resilient band having its ends connected together by a pin for confining the lower ends of the folded ribs and the lower edge of the folded balloon, said band opposing the tendency of the rib spreader to spread the ribs, a chamber communicating with the pin, an explosive charge in the chamber, a delay train of powder, and means for igniting the delay train.
